SHIP'S TELEGRAPH

Robert E. Friend, Chenequa, Wis., assignor to
Nordberg Manufacturing Co., Milwaukee, Wis.,
a corporation of Wisconsin

Substituted for application Serial No. 419,873,
November 21, 1941. This application April 19,
1945, Serial No. 589,143

5 Claims. (Cl. 116—21)

1

This invention relates to mechanical telegraphs used to transmit signals from the bridge of a ship to its engine room.

This application is a substitute application for application Serial No. 419,873, filed November 21, 1941, and abandoned October 4, 1944.

One object of the invention is to provide a mechanical ship's telegraph which will reduce the possibility of errors in the transmission of orders.

Another object is to provide a ship's telegraph which will eliminate the necessity of further action by the engineer after setting the engine as directed from the bridge.

A further object is to provide a ship's telegraph which will at all times indicate the setting of the engine.

Other objects will become apparent upon considering the following specification, which, when taken in connection with the accompanying drawing, illustrate one form of the present invention.

According to the invention a two way telegraph system is provided between the bridge and the engine room, said system including an indicator in the engine room and an indicator on the bridge, with means on the bridge to actuate the indicator in the engine room, and means coordinated with and actuated by the engine control means to operate the indicator on the bridge.

In the drawing:

Fig. 1 is a diagrammatic view in elevation of a mechanical ship's telegraph embodying the invention; and

Fig. 2 is a cross-section taken on the line 2—2 of Fig. 1, looking in the direction of the arrows.

Referring to the drawing in which like numerals indicate like parts in both views, the bridge telegraph, generally designated 10, may comprise a hollow pedestal 11, on which is mounted a cylindrical head 12. The head 12 has a dial 13 on one end thereof which indicates the desired orders to the engine room. A shaft 14 is mounted in the head and projects through the dial 13. An actuating lever 15, having an open central portion 16 and a handle 17, is keyed to the shaft 14 to turn it. A sprocket or pulley 18 is keyed on the shaft 14 for actuation by the handle 17. The sprocket or pulley 18 actuates a chain or cable 19 effecting a similar movement on the engine room telegraph, generally designated 20.

The engine room telegraph may be constructed of a cylindrical drum 21 having a dial 22 on one end thereof to indicate the order from the bridge telegraph 10. A shaft 23 is mounted axially in the drum and has a pointer 24 keyed thereto. A

2

sprocket or pulley 25 is keyed to the shaft 23, the sprocket or pulley 25 being actuated by the cable 19 from the bridge telegraph.

A double sprocket or pulley 27—28 is mounted to rotate freely on the shaft 23. The sprocket or pulley 27—28 is actuated by a belt or chain 29 operating between the sprocket or pulley 28 and a sprocket or pulley 30 carried by a shaft 31 and actuated by an engine control lever 32 which regulates the speed and direction of the engine (not shown).

The sprocket or pulley 27 which forms a part of the double pulley 27—28 carries a chain or cable 34, which engages a sprocket or pulley 35 on the shaft 14. The sprocket or pulley 35 is mounted to rotate relative to the shaft 14, and carries a pointer 36, which is adapted to show through the aperture 16 in the lever 15 to indicate when the order from the bridge to the engine room has been executed.

Similarly an indicator 40 is fixed to the hub of the double pulley or sprocket 27—28 and operates around the face of the dial 22 and indicates to the engineer that the engine control lever 32 is in position to execute the bridge officer's command.

In operation when the bridge officer wishes to transmit an order to the engine room he first moves the handle 17 across the uppermost position, which causes a hammer 38 to strike a bell 39 in the engine room telegraph 20 and call the attention of the engineer to a change in orders.

The handle 17 is then moved to the position desired. Movement of the handle 17 turns the sprocket or pulley 18 which causes a corresponding movement of the sprocket or pulley 25 and the pointer 24, causing the pointer 24 to indicate the same order as the handle 17.

The engineer then proceeds to make the appropriate setting by movement of the lever 32. Movement of the lever 32 to the position indicated on the dial 22 by the pointer 24 causes rotation of the double sprocket or pulley 27—28 which turns the sprocket or pulley 35 on the shaft

14. Turning the sprocket or pulley 35 causes the pointer 36 to turn to the position indicated by the speed of the engine, thus placing the pointer within the aperture 16 of the lever 15 when the desired setting of the lever 32 is made. At the same time the double sprocket or pulley 27—28 turns the indicator 40 so that when the proper engine setting is obtained the pointer 24 and the indicator 40 coincide.

Both the bridge officer and the engineer thus know from the setting of the pointer 36 and the

indicator 40 not only that the order has been received but that it has been correctly executed.

Having thus described the invention it is realized that it is susceptible to various changes and modifications. It is not, therefore, desired to limit the invention to the precise form herein shown and described but only by the scope of the appended claims.

The invention is hereby claimed as follows:

1. In a ship telegraph system, a bridge telegraph including a dial having desired orders indicated thereon, a lever movable to any of said indicated orders and a pointer movable to any of the orders indicated, an engine room telegraph including a dial having orders indicated thereon corresponding to the orders indicated on the bridge telegraph dial and a pointer movable to any of said orders, means actuated by said lever to actuate the pointer on the engine room telegraph, an engine control lever, and means actuated by the engine control lever to actuate the pointer on the bridge telegraph.

2. In a ship telegraph system, a bridge telegraph including a dial having desired orders indicated thereon, a lever movable to any of said indicated orders and a pointer movable to any of the orders indicated, an engine room telegraph including a dial having orders indicated thereon corresponding to the orders indicated on the bridge telegraph dial and a pointer movable to any of said orders, means actuated by said lever to actuate the pointer on the engine room telegraph, an engine control lever adapted to regulate the speed and direction of the engine, and a cable actuated by the control lever to actuate the pointer on the bridge telegraph.

3. In a ship telegraph system, the combination of a bridge telegraph including a dial having desired orders indicated thereon, a signal sending member movable to any of said indicated orders and an answer back member movable to any of the orders indicated, an engine room telegraph including a dial having orders indicated thereon corresponding to the orders indicated on the bridge telegraph dial and a signal receiving member movable to any of said orders and a signal sending member movable to any of the orders indicated, and an operator controlled engine control means movable to stop or change the direction of rotation of the engine and its speed, means actuated by the sending member on the bridge to actuate the receiving member on the

engine room telegraph, and means actuated by said engine control means to actuate the sending member of the engine room telegraph and the answer back member of the bridge telegraph.

5. In a ship telegraph system a bridge telegraph including a dial having desired orders indicated thereon, a lever movable to any selected one of said indicated orders and a pointer movable to any of the orders indicated, an engine room telegraph including a dial having orders indicated thereon corresponding to the orders indicated on the bridge telegraph dial and a pointer movable to any selected one of said orders, means actuated by said lever to actuate the pointer on the engine room telegraph from the bridge, an engine control lever adapted to regulate the speed and direction of the engine and means actuated by the movement of the control lever to actuate the pointer on the bridge telegraph to indicate the speed and direction of the engine.

10 15 20 25 30 35 40 45 50

6. In a ship telegraph system, a bridge telegraph including a dial having desired orders indicated thereon, a lever movable to any selected one of said indicated orders and a pointer movable to any of the orders indicated, an engine room telegraph including a dial having orders indicated thereon corresponding to the orders indicated on the bridge telegraph dial, a first pointer movable to any selected one of said orders, a second pointer on said engine room telegraph movable to any selected one of said orders, means to actuate the first pointer on the engine room telegraph by movement of said lever, an engine control lever adapted to regulate the speed and direction of the engine and means actuated by movement of the control lever to simultaneously actuate said second pointer on the engine room telegraph and the pointer on said bridge telegraph to indicate the speed and direction of the engine.
